ANGLE LEVEL

Willie E. Guffy, 25 W. Southport Road, Indianapolis, Ind.

Filed Nov. 29, 1963, Ser. No. 77,612

Term of patent 14 years

(Cl. DS2—6)

Fig. 2.

Fig. 1.

Fig. 3.

Fig. 4.

FIG. 1 is a front elevational view of an angle level, showing my new design.

FIG. 2 is an end elevational view thereof.

FIG. 3 is a top plan view thereof.

FIG. 4 is a rear elevational view thereof.

The opposite end of the angle level to that one shown in FIG. 2 is substantially the same in appearance as the one shown in FIG. 2.

I claim:

The ornamental design for an angle level, as shown and described.
